UNITED STATES PATENT OFFICE.

HAROLD E. BRADLEY, OF GREENWOOD, RHODE ISLAND, ASSIGNOR OF ONE-HALF TO MARION C. HAPPOLDT, OF PROVIDENCE, RHODE ISLAND.

ELECTRICAL FUSE-PLUG.

No. 904,832.

Specification of Letters Patent.

Patented Nov. 24, 1908.

Application filed January 8, 1908. Serial No. 409,181.

To all whom it may concern:

Be it known that I, HAROLD E. BRADLEY, a citizen of the United States, residing at Greenwood, in the county of Kent and State 5 of Rhode Island, have invented certain new and useful Improvements in Electrical Fuse-Plugs, of which the following is a specification, reference being had therein to the accompanying drawing.

10 My invention relates to electric fuse plugs of the class constructed with a fuse cartridge removably held in a casing, and has for its object to provide a simple and effective means whereby the cap for the case is prevented from being inadvertently removed therefrom before said case has been removed from its support or cut-out block.

In the practical use of fuses of this character the cartridge is first inserted into its 20 casing, the cap (which is of insulating material), is screwed onto the upper end of the casing, and said casing is then screwed into its block. When the cartridge has blown and it is desired to remove and replace the fuse 25 the cap, which forms a convenient handle, is naturally grasped by the hand and turned backwards in order to unscrew the case from said block, but in most instances the cap itself, which is only held by the friction of 30 the screw thread, will be the first to unscrew and come off, leaving the case still in position and in circuit. The operator usually then tries to remove the cartridge from the case, whereupon he is almost certain to receive a shock, which is, to say the least, very 35 unpleasant and in some cases where a heavy voltage is used, might prove fatal.

To obviate the above difficulty I have provided a lock for automatically connecting the 40 cap to the casing when said cap is applied thereto. The form of lock, as illustrated in the drawings, consists essentially in a spring tongue or lip on the casing as being adapted to engage a lug or tooth on the 45 cap by which the two parts may be automatically locked together. After the casing has been backed out of its block a slight pressure of the thumb or finger on this tongue at once releases the lock and the cap may be 50 removed from its casing exposing the cartridge which may then be removed and replaced without the slightest inconvenience or danger.

With these objects in view, the invention 55 consists of certain novel features of con-

struction, as will be more fully described and particularly pointed out in the appended claims.

In the accompanying drawings: Figure 1—is a side elevation showing the cap in 60 position on the casing and the spring tongue engaging one of the lugs on said cap. Fig. 2—is a central sectional view of the plug. Fig. 3—is a perspective view of the case showing the spring tongue raised from its 65 body portion. Fig. 4—is a perspective view of the cap showing a plurality of teeth which are adapted to engage said spring tongue to prevent the cap from unscrewing from the 70 casing.

Referring to the drawings, at 1 is the cut-out block which may be constructed in the usual way or in any suitable or convenient form, into which is screwed the threaded end 2 of the casing 3. This casing is usually 75 made with an outer shell of brass or other conducting material and lined with an insulating bushing 4. The lower end 5 is provided with a contact button which makes an 80 electric connection through the plate 6 in the cut-out block to the terminal 8. The upper end of this casing is also threaded as at 7 onto which the cap 10, which is preferably 85 made of insulating material, is designed to screw. The cap is provided with a lining of 90 conducting material. Into this casing is loosely fitted the fuse cartridge 11 which may be made in the usual form now on the market, the circuit passing from terminal 8, through button 6, cartridge 11, casing 3 and 95 terminal 9.

My improvement consists in the construction of a locking device for connecting the cap to its casing. Locking devices for this purpose may be constructed in many different ways but I have shown one simple and effective way which consists in cutting a strip of metal from the body of the casing leaving one end integral therewith, and raising the opposite end of the same forming a spring 100 tongue 12, best illustrated in Fig. 3. I also form one or more teeth or lugs 13—18 projecting from the inner end of the cap, which teeth are adapted to engage, depress and pass over said spring tongue as the cap is being screwed onto the casing, but when said cap is turned in the opposite direction one of the teeth will naturally come into contact with the end of said tongue and prevent the cap from being unscrewed until the tongue 110

has been depressed by the hand of the operator. By this construction it is at once apparent that the effective operation of the plug is not in any way interfered with by my improved attachment. The cartridge is inserted into the casing, the cap screwed onto the casing, and the casing in turn screwed into the cut-out block. When it is desired to remove the cartridge to examine or replace the same, the hand naturally grasps the insulated cap and turns the same back on the casing until one of the lugs brings up against the spring tongue whereupon the casing is unscrewed from its cut-out block, after which the little spring tongue is depressed by the thumb or finger of the operator and the cap at once removed. The cartridge may then be taken out and replaced completely obviating any possibility of receiving a shock during the operation.

I have shown and described a lock which consists essentially of a spring lip or tongue adapted to engage one or more corresponding projections on the cap, but I do not confine myself to this particular construction of a lock, as any means for preventing the accidental removing of said cap from said case will come within the spirit and scope of my invention.

Having thus described my invention, what I claim as new and desire to secure by Letters Patent, is:

1. An improvement in fuse plugs comprising a casing constructed to receive a fuse, a cap engaging one end of said casing, and means for locking said cap to said casing, said locking means being exposed below said cap, whereby the same may be manipulated manually to effect the disengagement of said cap from said casing.

2. An improvement in fuse plugs comprising a casing constructed to receive a fuse, a cap engaging one end of said casing, and

means formed integral with the casing for locking said cap to the casing, said locking means being exposed below said cap, whereby the same may be manipulated manually.

3. An improvement in fuse plugs comprising a casing constructed to receive a fuse, a cap engaging one end of said casing, and a spring tongue for locking said cap to said casing, said tongue being exposed below said cap, whereby the same may be manipulated manually.

4. An improvement in fuse plugs comprising a casing constructed to receive a fuse and provided with an exterior threaded portion, a cap engaging said threaded portion, and means for locking said cap to said casing; said locking means being exposed below said cap, whereby the same may be manipulated manually.

5. An improvement in fuse plugs comprising a casing constructed to receive a fuse and provided with an exterior threaded portion, a threaded cap engaging said threaded portion, and a spring tongue arranged to prevent reverse movement of said cap, said tongue being exposed below the cap, whereby the same may be manipulated manually.

6. An improvement in fuse plugs comprising a casing provided with a screw thread at each end, a spring tongue being formed integral with said casing and located intermediate of said ends, a cut out block threaded to receive one of said ends, and a threaded cap constructed to engage the other threaded end and provided with means for engaging said tongue, said tongue being located below said cap.

In testimony whereof I affix my signature in presence of two witnesses.

HAROLD E. BRADLEY.
